UNITED STATES PATENT OFFICE.

NOAH S. STEIN, OF BRISTOL, INDIANA.

ENGINE.

1,328,972.

Specification of Letters Patent. Patented Jan. 27, 1920.

Application filed February 2, 1918. Serial No. 215,143.

To all whom it may concern:

Be it known that I, NOAH S. STEIN, a citizen of the United States, residing at Bristol, in the county of Elkhart and State of Indiana, have invented a new and useful Engine, of which the following is a specification.

The subject of this invention is an engine in which pivoted or rocking cylinders are employed;

The main object of the invention is to reduce the number of moving parts of the engine;

Another object is to secure a more continuous and uniform action of the steam;

Another object is to eliminate the eccentric from an engine;

Still another object is to avoid dead centers;

Another object is to provide a simple, durable and efficient engine.

With the foregoing and other objects in view which will appear as the description proceeds, the invention resides in the combination and arrangement of parts and in the details of construction hereinafter described and claimed, it being understood that changes in the precise embodiment of the invention can be made within the scope of what is claimed without departing from the spirit of the invention.

A practical embodiment of the invention is shown in the accompanying drawings, wherein:—

Figure 1 is a side elevation of the engine, a portion of the cylinder being in section;

Fig. 2 is a plan view, a portion broken away;

Fig. 3 is a cross section on the line 3—3 of Fig. 2;

Fig. 4 is a fragmentary detail taken on the line 4—4 of Fig. 3;

Fig. 5 is a similar view taken on the line 5—5 of Fig. 3;

Fig. 6 is a similar view taken on the line 6—6 of Fig. 3.

Fig. 7 is a view showing, in diagram, the arrangement of the fixed and movable inlet and exhaust ports.

Referring to the drawings by numerals of reference:—

In carrying out the invention a bed plate 10 is provided which is formed with upstanding sides 11 at each end of which sides 12 journaling blocks are provided. Lateral

extensions 13 are formed at the longitudinal center of the bed plate and from the outer end of each extension 13 rises a standard providing a journaling block 14.

The sides 11 of the bed plate are preferably extended upwardly at their centers and are offset inwardly as indicated at 15, Fig. 3. These offsets are vertically bored to receive the cylindrical intake valves 16, four of which are provided, and the outlet valves 17, which are likewise four in number.

The opposed faces of the offsets or extensions 15 are tapped adjacent each end and near the top to receive nipples 18 which communicate with the bores in which the intake valves turn and which extend from a T-joint 19. The T-joints 19 are connected through horizontally disposed pipes 20 with a T 21 from which an intake pipe 22 extends upwardly.

These opposed walls are also tapped toward each end and near their lower edges to receive nipples 23 which extend from T-joints 24 and communicate with the bores in which the exhaust valves 17 turn. The T-joints 24 are connected through horizontally disposed pipes 25 with a T 26 from which the exhaust pipe 27 extends downwardly.

The side walls 11 are provided with upper and lower apertures 28 which communicate with the bores in which the inlet valves 16 turn, and also with upper and lower ducts 29 which communicate with the bores in which the exhaust valves 17 turn.

A cover or top 30 is seated on this central portion of the sides 11 and is secured thereto by screw bolts 31 or otherwise. This top is provided with a series of apertures through which project the stems 32 of the inlet and exhaust valves.

A mutilated gear 33 is secured to each projecting stem of the inlet and exhaust valves. These mutilated gears mesh with racks 34 formed on bars 35 which are mounted to reciprocate longitudinally of the engine through guides 35'. By sliding the bars 35 to the position shown in Fig. 2 the valves are set to cause the engine to run over or forward, while sliding the bars to the opposed position reverses the engine.

A segmental rack 36 is secured to and rises from the top 30 and to this rack is pivotally secured a lever 37, which lever is connected by a link 38 to a tie plate 39 which extends

between and is secured to the bars 35. The lever 37 is, as will be understood, the reversing lever.

The inlet valves 16 are provided with 5 upper ports 40 which are positioned to register with the inlet nipples 18 in either position of the valves. These valves are also provided with upper and lower ports 41 which alternately register with the upper and lower bores 28 upon reverse and forward movement of the engine, respectively.

The exhaust valves 17 are provided with ports 42 which register with the outlet or exhaust nipples 23 in either position of the valves, and also with upper and lower ports 43 which register with the upper and lower bores 29 upon forward and reverse movement of the engine, respectively.

A cylinder 44 is mounted on each side of 20 the bed plate between the upstanding side 11 and the standard at the end of projection 13, and each cylinder is provided with trunnions 45 which oscillate in the journaling blocks 14 and blocks 46 formed on the 25 inner face of each side 11. Each cylinder is of irregular external formation and presents a flat surface 47 to the outer face of each side 11.

A piston 48 is provided in each cylinder 30 and is mounted centrally of a piston rod 49 which has at each end a journaling member 50 in which turns the pin of a crank 51 secured to a shaft 52 which is journaled in the blocks 12. A fly wheel 53 may be provided on each shaft.

On one shaft 52, which will be termed the drive shaft, is fixed a beveled gear 54 which meshes with a beveled gear 55 secured to the 40 end of a shaft 56 which may be suitably journaled in the bed plate and convey power from the engine to desired parts.

Each cylinder has a pair of apertures 57 formed adjacent each end and adapted to register with the apertures or bores 28 during 45 certain periods of the oscillation of the cylinders.

A pair of apertures 58 is also provided adjacent each end of each cylinder and these apertures are adapted to register with the 50 bores 29 during certain periods of the oscillation of the cylinders.

Each cylinder is also provided, near each end, with a by-pass 59 which permits the expanding steam to escape to the advancing 55 face of the piston just before the end of a stroke so as to relieve the pressure on the rear of the piston and cause a smooth and even reversal of motion.

By referring to Fig. 7 it will be noted 60 that the movable ports 57 and 58 carried by the cylinder have been designated by the letters *a*, *b*, *c*, and *d*. In said figure the stationary inlet ports have been indicated at 28^a, 28^b, 28^c and 28^d, while the stationary 65 exhaust ports have been indicated at 29^a,

29^b, 29^c and 29^d. Assuming that the crank 51 is moving downwardly from the position shown in Fig. 1, during the first half rotation of the crank, the port 57^a will move downwardly into register with the open inlet port 28^a while the port 58^a will move downwardly into register with the closed exhaust port 29^a. At the same time the port 57^c will move upwardly into register with the closed inlet port 28^c and the port 58^c will move upwardly into register with the open exhaust port 29^c. Thus pressure entering the registering ports 28^a and 57^a will drive the piston longitudinally and allow steam at the other side of the piston 80 to exhaust through the ports 58^c and 29^c. During the second half of the rotation of the crank the cylinder will be rocked so as to reverse its position, bringing the port 57^d into register with the closed inlet port 85 28^b and bringing the exhaust port 58^d into register with the open exhaust port 29^b. At the same time port 57^a will be brought into register with the open inlet port 28^d while the port 58^d will move into register with the 90 closed exhaust port 29^d. Thus pressure will be directed against the opposite end of the piston and a complete cycle of rotation will be effected. By shifting the lever 37 the racks 34 are moved longitudinally so as to 95 rotate the valves 16 and 17 to close one of the ports of each valve and open the other port thereof. This will result in the prompt reversal of the engine, as will be obvious.

It will be noted that the only movement 100 of the valves takes place when the engine is reversed or stopped, consequently no eccentric is required.

Having thus described the invention, what is claimed as new and sought by Letters 105 Patent, is:—

An engine including a bed plate formed with upstanding sides, spaced pairs of valve casings formed in each of the sides, each of said casings being provided with upper and lower ports, an intake valve in one casing of each pair and having upper and lower non-alining ports movable into and out of register with the corresponding ports in the casing of the valve, an outlet valve in the other casing of each pair and having upper and lower non-alining ports movable successively into register with the corresponding ports in its casing, gears connected to and revoluble with the respective valves, racks 110 engaging the gears, means for moving the racks to rock the valves, cylinders mounted to rock at the respective sides of the bed plate about an axis extending between the spaced pairs of valve casings, a pair of ports 115 in the side of the cylinder at each side of the axis and between and movable successively into register with the adjacent intake ports in the bed plate, and a pair of ports at each side of the axis of the cylinder and 120

125 130

opening into the cylinder, said last named ports working between and being movable successively into register with the adjacent outlet ports in the bed plate, pistons in the 5 cylinders and rods extending from the pistons.

In testimony that I claim the foregoing as

my own I have hereto affixed my signature in the presence of two witnesses.

NOAH S. STEIN.
